UNITED STATES PATENT OFFICE.

JUAN C. MONTERO, OF WASHINGTON, DISTRICT OF COLUMBIA.

INDICATOR.

1,414,298.

Specification of Letters Patent. Patented Apr. 25, 1922.

Application filed September 18, 1918. Serial No. 254,585.

To all whom it may concern:

Be it known that I, JUAN C. MONTERO, a citizen of the United States, residing at Washington, District of Columbia, have invented new and useful Improvements in Indicators, of which the following is a specification.

My present invention has to do with float actuated, electro - mechanical indicating means; and its general object is the provision of means, of the character defined, designed to put a person in authority on notice regarding the quantity of fluid in a tank and the stages of the fluid as the supply is depleted, this with a view to apprising such person at all times of the amount of fluid available and precluding the possibility of the supply of fluid being entirely exhausted through oversight on the part of those in authority.

The invention is primarily designed for installation in motor vehicles and to inhibit any possibility of the motorist failing to replenish the supply of gasoline when the same is needed; and its novelty, utility and practical advantages will be fully understood from the following description and claims, when the same are read in connection with the drawings, accompanying and forming a part of this specification, in which:

Figure 1 is a perspective, partly in section, illustrative of the manner in which my improvement is installed in an automobile.

Figure 2 is a diagrammatic view of the general arrangement.

Figures 3 and 4 are diametrical sections taken at right angles to each other and showing the float casing and its contents.

Figure 5 is an enlarged detailed diametrical section showing the construction adjacent to the upper end of said casing.

Figure 6 is a detailed plan of the head in said casing.

Figure 7 is a horizontal section taken in the plane indicated in the line 7—7 of Figure 3, looking downwardly.

Figure 8 is an enlarged detailed view showing the specific construction of the circuit breakers.

Figures 9 and 10 are sectional views of a modification hereinafter explicitly referred to; Figure 10 being taken in the plane indicated by the line 10—10 of Figure 9, looking downwardly.

Referring by numeral to said drawings

and more particularly to Figures 1 to 8 thereof:

1 is the dash of an automobile. 2, Figure 1, is the gasoline tank which may be located in the automobile at any point compatible with the purpose of my invention, and 3 is a casing, located, by preference, on the rear side of the dash 1 where it will be in plain view of the automobile driver. 50 is a conductive casing arranged in and adapted to receive gasoline from the tank 2.

For the sake of convenience, I will first describe the general scheme of my invention in connection with the diagrammatic showing in Figure 2. By reference to said figure it will be understood that the casing 50 is connected through a wire 4 (see also Figure 6) with one pole of a source of electric energy 5, and that the other pole of the source of energy is connected through a wire 6 with an incandescent electric lamp 7, which lamp 7, in turn, is connected through a wire 8 with a terminal 9. Opposed to the terminal 9 and normally spaced therefrom is a terminal 10 of a float 11, supported by gasoline in the casing 50. By virtue of this provision it will be manifest that when the tank 2 and casing 50 are fully charged, the float 11 will be raised to carry the terminal 10 into contact with the terminal 9, whereupon the lamp 7 will be caused to glow. The lamp 7 will remain lighted until the quantity of gasoline is diminished to an extent necessary to break the contact between the terminals 10 and 9, and from this it follows that so long as the lamp 7 glows the driver or other person in authority will be apprised of the fact that there is a full charge of gasoline in the tank in which the casing 50 is disposed.

In furtherance of my invention, a number of floats 12, 13, and 14 are associated with the float 11 in the casing 50, each of the said floats 12, 13 and 14 being provided with a terminal 15, and each terminal 15 being designed to be used in conjunction with a complementary individual terminal 16. I also provide a switch member 17 and an electric bell 18, said bell being electrically connected through a wire 20 with the opposite side of the source of energy 5, with reference to the wire 4. A branch wire 19 is interposed between the member 17 and a switch member 32. In conjunction with the switch member 17 I employ a group of terminals 21, corresponding in number to 310

the floats disposed in the casing 50, and I also employ a similar number of circuit makers and breakers 22, each of which is preferably of the construction shown in Figure 8, and is made up of an electro-magnet 23, a swing armature and latch 24, spring pressed at 25, a gravitating annunciator 26, and a vertically swinging link 27 through the medium of which the annunciator is connected with the magnet frame. Each electro-magnet 23 is connected through a wire 28 with the terminal 21 complementary to the magnet, and in proper relation to each annunciator is arranged a resilient or otherwise movable terminal 29, which normally contacts with the annunciator, as indicated in full lines in Figure 8 and is electrically connected through a wire 30 with the terminal 16 complementary to the magnet.

When the electric lamp 7 ceases to glow, the automobile driver or other person in authority is apprised of the fact that it is his province to place the switch member 17 in contact with the terminal 21 of the annunciator 22 that is complementary to the float 11. By virtue of this arrangement when the quantity of gasoline in tank 2 is depleted to a certain extent and the terminal 10 of the uppermost float 11 makes contact with the adjacent terminal 16, the first magnet to the left in Figure 2 will be energized and the bell 18 will be briefly sounded, and hence the driver will be informed that he has used up his first predetermined portion of gasoline. The brief sounding of the bell 18 is due to the fact that when the electro-magnet is energized to attract the armature 24, the gravitating annunciator 26 falls and moves the terminal 29 from the position shown by full lines into the position shown by dotted lines in Figure 8, with the result that the circuit is broken by reason of the gap created between the terminal 29 and the annunciator. When the bell 18 is first sounded, as stated, it is the province of the driver to swing the switch member 17 into contact with the second terminal 21 towards the right so as to inform the driver when the second portion of gasoline has been taken from the tank. Then when the bell sound to indicate the removal of the second portion, it is the province of the driver to swing the member 17 into contact with the third terminal 21 towards the right, and then when the driver is informed of the removal of the third portion of gasoline it is his duty to move the member 17 into contact with the fourth and last terminal 21 towards the right. When this latter duty is performed and the float 14 moves downwardly, incidental to the removal of the lowermost portion of gasoline from the tank, the electric bell 18 will continue to ring. This latter

is due to the fact that the last electro-magnet 23 towards the right in Figure 2 has one end of its helix connected directly through a wire 35 with the terminal 16 adjacent to the terminal 15 of the float 14 and also has its opposite end connected through a wire 36 with the fourth terminal 21. In other words, the said last electro-magnet 23 towards the right in Figure 2 is not combined with a terminal 29, and, consequently, when said magnet 23 is energized the energization and the ringing of the bell 18 will continue until the circuit is broken by moving a switch member 31. The magnet 23 just referred to is shown at the right 75 of Figure 2 as minus a terminal 29. Each of the gravitating annunciations bears a number, as shown in Figure 2; the said numbers being arranged in regular sequence from left to right and being provided in order to inform the driver, of the particular float through which the particular circuit is completed for the ringing of the bell 18.

The switch member 31 normally contacts with a terminal 33, electrically connected at 34 with the side of the bell 18 remote from the conductor 20, so that the operator can stop the ringing of the bell 18 when desired.

For the purpose of conveniently resetting the circuit makers and breakers and to raise the annunciator members 26, I employ in conjunction with the several links 27 the resetting device clearly shown in Figures 100 2 and 8 as made up of a rock-shaft 40, having a handle 41 at one end and fingers 42, one for each link 27. Manifestly, when said shaft 40 is manually rocked in the direction indicated by the arrow in Figure 105 8 the several links 27 will be raised in concert to elevate the gravitating elements 26 and replace the same in engagement with the catches on the armatures 24.

When any one of the floats 11, 12, 13 or 110 14 drops sufficiently to carry its terminal into contact with the adjacent stationary terminal the circuit will be from the plus pole of the source of energy through the wire 4, the casing 50, the particular float 115 that brought about the contact, the terminal 16 complementary to said float, the wire 30 or 35, the terminal 29 adjacent to the magnet belonging to the particular float, and from said magnet through the wire 23, the terminal 21, the switch member 17, the electric connection 19, the electric bell 13 and the wire 20 back to the minus pole of the source of energy.

In the preferred embodiment of my invention the several floats 11, 12, 13 and 14 are disposed in a casing 50, that is arranged in pendent position in the tank 2; there being metallic connections between all of the floats 11, 12, 13 and 14 on the one 130

hand and the said casing 50, on the other, as shown in Figure 4. This specific installation of my invention involves the provision or employment of a diametrical partition 51 in the casing, together with guide brackets 52 on said partition; the floats 11 and 13 being disposed at one side of said partition, and the floats 12 and 14 at the opposite side thereof. As shown in Figures 3 and 4, there are metallic connections between the several floats and the metallic casing 50, and there is a direct metallic connection between the said casing 50 and the top of the tank 2, Figure 1. Thus the 10 floats are grounded on the tank as indicated conventionally in Figure 2. The stems of the several floats are carried through large apertures 53 in the preferably flanged head 54 of the casing 50, and below and above said head insulating plates 55 and 56 are suitably secured. It will also be noticed that the float stems are provided with hook-like terminals 10 and 15, corresponding to the terminals 10 and 15 of 20 the showing in Figure 2, and that stationary terminals 16 corresponding to the terminals 16 of the Figure 2 are super-imposed and suitably secured on the upper insulating plate 56. Secured on the said insulating plate 56 is a terminal 9 corresponding to the stationary terminal 9 at the left of Figure 2. On the head 54 which protrudes through the top of the tank 2 is a cap 60, having a central orifice 61, and through the 30 said orifice are carried the several wires complementary to the stationary terminals, as clearly shown in Figures 1, 3 and 4.

In the modified embodiment shown in Figures 9 and 10 the casing 50^a is slotted at 40 two points, as indicated by 70, and contains a float 71. Arms 72 and 73 are arranged to play in said slots, at opposite sides of the float 71; the said arms being carried by a vertically movable rod 74. This rod is normally maintained in raised 45 position by a spring 75, and is equipped with a terminal arm 76 bearing contact points 77 and 78. The said contact points are interposed between the arms of a U-shaped terminal member 79. The said U-shaped member 79 is connected through a wire 80 with an electric bell 81, and said bell 81, in turn, is connected through a wire 82 with one pole of a source of energy 83, 55 and the opposite pole of the source of energy is connected through a wire 84 with the casing 50^a. It will also be noticed in Figure 9 that the lamp 7^a is arranged in parallel with the bell 81 in the conductor 60 80, so that the lamp will be caused to glow co-incident with the sounding of the bell. In the modified arrangement when the float is maintained in its uppermost position by a full supply of gasoline in the tank containing the casing 50^a, the float will act

against the upper arm 72 and carry the upper contact 77 in engagement with the upper arm of the terminal 79, and, in consequence, the lamp 7^a will be caused to glow and the bell 81 to ring until the level of the 70 gasoline in the tank is lowered. When, on the other hand, the float 71 is permitted by the depletion of the gasoline to move downwardly sufficiently far to engage the arm 73 and to depress the rod 74 against the 75 action of the spring 75, the lower contact 76 will engage the arm 79 and the same result will be brought about.

It will be gathered from the foregoing that my novel indicator is calculated to 80 preclude the possibility of an automobile driver or other person in authority forgetting to replenish the supply of gasoline in the tank when occasion demands; and I would also have it distinctly understood 85 that while my improvement is designed primarily for use in conjunction with the gasoline tank of an automobile, the improvement may be put to any other use to which it is applicable without involving departure 90 from the scope of my invention as defined in my appended claims.

When the capacity of function of my novel indicator is taken into consideration the simplicity of the apparatus will be fully 95 appreciated; and it will also be noted that the apparatus embodies no delicate parts such as are likely to get out of order when subjected to the vibration and the shocks and jars usually attendant on the operation 100 of an automobile.

Having described my invention, what I claim and desire to secure by Letters Patent is:—

1. In an electro-mechanical float indicator, the combination of a plurality of floats arranged to be controlled by different portions of liquid, a terminal on each float, terminals complementary to the float terminals, a second terminal complementary to the terminal of the uppermost float, and arranged in a normally open electric circuit with a source of electric energy, the float and a lamp, and annunciators, one to each float, arranged in a normally open electric circuit, with one of the second named terminals, a source of electric energy and an audible electric signal.

2. An electrical installation, comprising a movable switch member, a plurality of terminals complementary thereto, a plurality of annunciators, a second switch member, a terminal complementary thereto, an electric signal, a plurality of circuit closing devices, arranged in normally open electric circuits with a source of energy, the signal, the switch members, the terminals and the annunciators, floats controlling the closure of said circuits, an additional electric signal, and an additional terminal arranged in an 130

initially complete circuit with the source of energy, the additional signal and one of the float-controlled circuit closers.

3. In an electro-mechanical indicator of the float type, the combination of a casing, a partition therein and provided with guides, floats arranged at opposite sides of said partition and in different horizontal planes, terminals on the floats, and terminals cooperating with the float terminals, respectively, on and insulated from the casing.
- 10 4. In an electro-mechanical indicator of

the float type, the combination of a casing, a partition therein, floats arranged in the casing at opposite sides of the partition and 15 placed in different horizontal planes, terminals on the floats, terminals on the casing and insulated from the same; and an auxiliary terminal cooperating with the terminal of the uppermost float mounted on the casing in opposed relation to the first mentioned cooperating terminal.

In testimony whereof I affix my signature.

JUAN C. MONTERO.
